UNITED STATES PATENT OFFICE.

ANDREW T. RICHARDSON, OF VERONA, PENNSYLVANIA, ASSIGNOR TO VERONA TOOL WORKS, OF VERONA, PENNSYLVANIA, A CORPORATION OF PENNSYLVANIA.

LIFTING-JACK.

1,143,067.

Specification of Letters Patent. Patented June 15, 1915.

Application filed April 15, 1914. Serial No. 832,014.

To all whom it may concern:

Be it known that I, ANDREW T. RICHARDSON, a citizen of the United States, and resident of Verona, in the county of Allegheny and State of Pennsylvania, have invented a new and useful Improvement in Lifting-Jacks; and I do hereby declare the following to be a full, clear, and exact description thereof.

10 My invention relates to lifting-jacks.

The object of my invention is to provide a simple and efficient form of lifting-jack in which the jack is raised by a step-by-step movement and also lowered in the same

15 manner.

In the accompanying drawing, Figure 1 is a side view partly broken away illustrating the jack and showing the position of the parts when the jack is arranged for 20 lifting a load; Fig. 2 is a like view showing the position of the parts when the jack is arranged for lowering the load; Fig. 3 is a section on the line 3—3 Fig. 1, and Fig. 4 is a perspective view of the pendulum.

25 The frame or stand 2 of the jack has formed therein the bearings 3 for the pin 4 on which the operating lever 5 is mounted. The lower-pawl 6 is pivotally mounted on the inner end of the lever 5. The upper-pawl 7 is suspended from the upper end of the frame 2, being mounted on the studs 8. The said pawls are so mounted as to normally fall by gravity toward the lifting-bar 9, and into engagement with the teeth 10 35 of said lifting-bar. The lifting-bar is enclosed within the frame 2 and said bar is provided with the vertical grooves 9 which engage guide-ribs on the interior of the frame in the ordinary manner.

40 The weighted pendulum 11 is pivotally mounted on the cam 12 in the side of the frame and at the lower end of said pendulum is the weight 13. A handle 14 on the cam 12 extends outside the frame and by 45 the turning of said handle the cam is operated to throw the pendulum into reversing position. The pendulum has the finger 15, which in the reverse position of said pendulum, is adapted to engage the stud or lug 16 50 on the upper pawl 7, and said pendulum has cam-face 17 which is adapted to engage the stud or lug 18 on the lower pawl 6 when in reversing position. The weight 13 at the lower end of the pendulum is contained 55 within the frame, and said weight acts to

operate the cam-arm automatically when in reversing position.

In raising a load with my improved jack, the cam-arm is in the position indicated in Fig. 1, and on raising and lowering the handle 5, the lifting-bar is raised by a step-by-step motion, the lower-pawl raising the lifting-bar, and the upper-pawl falling into position to hold the bar in this raised position until the lower-pawl has engaged another tooth. When it is desired to reverse and lower the lifting-bar by a step-by-step motion, the handle 14 of the cam 12 is turned and the cam-arm 11 is thrown forward so that its upper finger 15 will engage 65 the stud 16 of the upper-pawl 7 and its cam portion 17 will be in the path of the stud 18 of the lower-pawl 6. Accordingly as the handle 5 is raised the lower-pawl in its descent comes in engagement with the cam-portion 17 of the cam-arm 11, and said lower-pawl is thrown out of engagement 70 with the tooth of the lifting-bar, while the upper-pawl moves by gravity into engagement with one of the teeth of the lifting-bar, the finger of the cam-arm 11 being thrown back to permit of this falling of the upper-pawl into engagement with the teeth of the lifting-bar. This movement of the finger is due to the weight of the load bearing 75 on the lower pawl, and the movement of the stud 18 along the cam portion 17, said stud moving in a downward course, will act to force the finger back. As this movement of the hand-lever 5 is repeated 80 a like operation takes place and the lifting-bar is lowered by a step-by-step movement until the bar is lowered the desired distance.

In case it is desired to release the lifting-bar so that it will drop suddenly the cam-arm 11 is thrown to its normal position, and the lower-pawl is lowered and moved out to engage the notch 20 on the lower end of the upper pawl, whereupon both pawls are held out of engagement with the 85 lifting-bar and said lifting-bar will drop.

What I claim is:

1. In a lifting jack, the combination with a suitable frame, of a toothed lifting bar, an operating lever, a lower pawl pivotally mounted on said operating lever, an upper pawl suspended from said frame, a pendulum mounted in the frame having a weighted portion at the lower end, a finger at the upper end, and a cam portion intermediate 100

said weighted portion and said finger, projections on the upper and lower pawls adapted to engage said finger and cam portion respectively, means for throwing said 5 pendulum in position for engagement by said projections.

2. In a lifting jack, the combination with a suitable frame, of a toothed lifting bar, a hand-lever, a lower pawl pivotally mounted 10 on said hand-lever, an upper pawl suspended from said frame, a cam, a pendulum pivotally mounted on said cam having a

weight at its lower end and a finger at its upper end, and a cam portion above said cam intermediate said weight and said finger, and projections on said upper and lower pawls adapted to engage the said finger and said cam portion respectively. 15

In testimony whereof, I, the said ANDREW T. RICHARDSON, have hereunto set my hand. 20
ANDREW T. RICHARDSON.
